UNITED STATES PATENT OFFICE.

FREDERICK WOLF, OF PHILADELPHIA, PENNSYLVANIA.

IMPROVEMENT IN SAFETY-BRAKES FOR RAILROAD-CARS.

Specification forming part of Letters Patent No. 44,361, dated September 20, 1864.

To all whom it may concern:

Be it known that I, FREDERICK WOLF, of the city of Philadelphia, and State of Pennsylvania, have invented new and useful Improvements in Safety-Brakes for City Passenger Railway-Cars; and I do hereby declare that the following is a full and exact description thereof, reference being had to the accompanying drawings, and to the letters of reference marked thereon, in which—

Figure 1 is a bird's-eye view of the car-truck. Fig. 2 is a side view of the same. Fig. 3 is a view of the slotted guide-plate D. Fig. 4 are views of the shoes of the brake.

Similar letters in the figures represent same parts.

The invention consists in providing for a city passenger railway-car a safety-brake, operated upon solely by an object or obstruction upon the track in front of the car-wheels, rendering it impossible to drag the car over such obstruction.

To enable others skilled in the art to make and use my invention, I will proceed to describe and explain its construction and operation.

By referring to the drawings, A represents the frame of the car-truck. B B is an additional frame, supported wholly upon the axles of the car-wheels, and confined to its position by means of straps around the axles. The object of placing this frame on the axles is, that the brake-shoes may be independent of the car-springs and load, and will always present the same height from the track when not in operation, which could not be if they were attached to the car-body or truck-frame A. Attached to the ends of this frame are the slotted or grooved plates D D. In these grooves e e are hung the self-acting shoes of the brakes C C by means of the rollers or studs a a. The shoes are held up free from the

track and car-wheels by means of the spiral springs c c. Should an object of light weight and small bulk be upon the track, the movable or yielding broom b will displace it. An object of greater bulk and weight will overcome the power of the spring c and force the shoe against the track and partially under the wheel, thereby locking it and forcing the object forward until the momentum of the car is arrested. The object can now be removed from the track, the car slightly backed, and the shoe, being liberated, will instantly resume its former position by the action of the spiral spring c. The movable or yielding broom b, as seen in Fig. 4, is attached to the end of a bar inserted into the perpendicular socket C and adjusted to its proper height above the track by pins and slots d d. It might be necessary to regulate the height of the broom by a spring within the socket.

In applying this safety-brake to a dummy or steam passenger-car the shoe C would require to be attached to the forward end of a car only. From these shoes I propose a connection with a throttle-valve in the steam-pipe leading to the cylinder, so that by their action the steam would be immediately cut off when an obstruction is placed in front of the wheels.

What I claim is—

1. A self-acting shoe hung upon a stud or roller working in a grooved or slotted plate, as shown and described, for the purpose set forth.
2. Supporting the frame B, to which are attached the grooved or slotted guide-plates D, by the axles of the car wheels, as and for the purpose specified.

FREDERICK WOLF.
